WILLIAM S. BIDLE AND JOSEPH A. COSTELLO, OF CLEVELAND, OHIO, ASSIGNEES TO CLEVELAND CAR SPECIALTY COMPANY, OF CLEVELAND, OHIO, A CORPORATION OF WEST VIRGINIA.

CAR-ROOF CONSTRUCTION.

1,049,041.

Specification of Letters Patent. Patented Dec. 31, 1912.

Application filed March 31, 1911. Serial No. 618,062.

To all whom it may concern:

Be it known that we, WILLIAM S. BIDLE and JOSEPH A. COSTELLO, citizens of the United States of America, residing at Cleveland, in the county of Cuyahoga and State of Ohio, have invented certain new and useful Improvements in Car-Roof Construction; and we do hereby declare the following to be a full, clear, and exact description 10 of the invention, such as will enable others skilled in the art to which it pertains to make and use the same.

This invention relates to improvements in car-roofs and pertains more especially to 15 an improved car-roof construction for a box-car employed in the shipment of freight.

The primary object of this invention is to prevent the blowing of snow and rain 20 by the wind into a box-car at the joints formed between the component parts of the roof of the car.

Another object is to construct a car-roof whose component parts are readily assembled and secured in place.

Another object is to make a car-roof which is exceedingly simple and durable in construction.

Another object is to make a car-roof 30 which is easily kept in good condition.

With these objects in view, and to the end 35 of attaining other advantages hereinafter appearing, this invention consists in certain structural features, and combinations and arrangement of parts, hereinafter described, pointed out in the claims, and illustrated in the accompanying drawings.

In the said drawings, Figure 1 is a top plan of the left-hand end-portion of a car-roof embodying our invention. Fig. 2 is a top plan of the right-hand end-portion of a car-roof embodying our invention. Fig. 3 is a vertical section on line 3—3, Fig. 1, looking in the direction indicated by the arrow. Fig. 4 is a vertical section on line 4—4, Fig. 3, looking in the direction indicated by the arrow. Fig. 5 is a vertical section on line 5—5, Fig. 1, looking in the direction indicated by the arrow. Fig. 6 is a vertical section on line 6—6, Fig. 1, looking in the direction indicated by the arrow. Fig. 7 is a vertical section on line 7—7, Fig. 5, looking in the direction indicated by the arrow. Fig. 8 is an approximately horizontal section on line 8—8, Fig. 4, looking

downwardly. Fig. 9 is a vertical section on line 9—9, Fig. 7, looking outwardly. Fig. 10 is a horizontal section on line 10—10, Fig. 7, looking downwardly. Fig. 11 is a horizontal section on line 11—11, Fig. 7, looking downwardly. Portions are broken away in the drawings to reduce the size of the same and to more clearly illustrate certain features of construction, and Figs. from 3 to 11 inclusive are drawn on a larger scale than Figs. 1 and 2.

The framework of our improved car-roof, as shown in Figs. 1 and 2, comprises two laterally spaced side plates A and A which extend longitudinally or endwise of the car-roof and are arranged substantially horizontally and parallel. The said side plates are connected together at their ends by beams or rafters B. Under each side plate A, at each end of the frame of the car-roof, is arranged a post C, and at the outer side of each side plate A is arranged upright car-siding D which overlaps and abuts against the outer side of the said side plate and terminates at the top thereof a suitable distance below the top of the side plate.

Metal carlines E are arranged transversely and spaced longitudinally of the car-roof, being arranged between and spaced from the ends of the car-roof. That is, the carlines E are spaced laterally between the end beams or rafters B of the frame of the car-roof. Each carline E bridges the space between and is supported from the side plates A which are preferably recessed, as at a, in the tops thereof and transversely from side to side thereof to receive the said carline.

The carlines E are therefore set into the side plates A at the top of the side plates and are thereby prevented from displacement endwise of the side plates. Each carline E at the outer side of each side plate A has a downwardly projecting end-portion e arranged at and overlapping and abutting against the outer side of the car-siding D adjacent the said side plate. Each carline E is preferably trough-shaped substantially from the top and outer side of the car-siding at the outer side of each side plate A to the top and outer side of the car-siding at the outer side of the other side plate. One of the carlines is shown exposed in Fig. 2, and the shape of the carlines is also shown in Figs. 3, 4, 5, 7, 8, 9, 10 and 11. Each carline E at the top

70

75

80

110

thereof slopes from the outer side of each side plate upwardly to a point centrally between the ends of the carline. Each carline E is provided externally with two laterally 5 and outwardly projecting flanges 15 and 15 which are arranged at opposite sides respectively of the carline and extend longitudinally of the carline and along the top of the carline from the outer side of each 10 side plate A to the outer side of the other side plate. As shown in Figs. 7 and 10, each flange 15 projects downwardly, as at 16, at the outer side of each side plate A and abuts against the outer side of the said side 15 plate and thence extends laterally and outwardly, as at 17, over and in close proximity to the top of the car-siding D adjacent the said side plate and to the outer side of the said car-siding. Each carline E is rigidly 20 secured at the flanges 15 thereof by suitably applied bolts 18 and nuts 19 to the side plates A.

By the construction hereinbefore described it will be observed that the carlines 25 E efficiently tie or connect the side plates A together, that each side plate is materially reinforced at its outer side and above the adjacent car-siding D by the adjacent downwardly projecting portions 30 16 of the flanges 15, and that the said downwardly projecting portions of the said flanges afford a lateral abutment or bearing for the outer side of the said side plate.

The relative arrangement of the parts 35 is preferably such that the flanges 15 where they extend across or transversely of each side plate are flush at their upper sides with the top of the said side plate, as shown in Fig. 9. Each flange 15 of each carline 40 E is (see Figs. 3 and 4) depressed and somewhat increased in width centrally between the ends of the carlines to form a pocket or depressed seat 20 for the ridge-pole F of the car-roof, which ridge-pole 45 extends in the usual manner longitudinally of the car-roof and is arranged centrally between and parallel with the side plates A. Each flange 15 at a plurality of points between the ridge-pole-receiving pocket or 50 seat 20 of the carline and each side plate A is depressed and somewhat increased in width to form a pocket or depressed seat 22 (see Figs. 3, 5, and 7) for purlins H of the car-roof, which purlins extend longitudinally of the car-roof and are parallel 55 with the ridge-pole F and side plates A.

The side plates A, the end beams or 60 rafters B, the carlines E, and the space between the side plates from end to end of the car-roof are covered by sheet-metal roofing which comprises sheet-metal roofing-sections L and sheet-metal caps M, and it will be observed that two suitably-supported sheet-metal roofing-sections L extend from 65 over each carline laterally of the said carline

in opposite directions respectively and also extend longitudinally of the carline over and beyond the outer sides of the side plates, and each roofing-section L at the outer side of each side plate (see Figs. 3, 5, 7, 9, 10 and 11) has a downwardly projecting end-portion 7 arranged at the outer side of the adjacent downwardly projecting end-portion 6 of the said carline. 70

Each roofing-section L curves or slopes, 75 as at 23, (see Figs. 3, 5 and 9) upwardly over the said carline to a point substantially central between the sides of the carline,—that is, between the flanges 15 of the carline,—and at the said point has an upwardly projecting side portion 24 which extends longitudinally of the said carline and terminates in a flange 25 which projects laterally of the said side portion over and is spaced from the body of the said roofing-section, which flange extends longitudinally of the said side portion of the said roofing-section and has a downwardly bent portion 26 extending longitudinally of the flange. Each end roofing-section, as 80 shown in Fig. 6, of course projects downwardly, as at 14, at the outer side of the car-siding 13 arranged at the outer side of the adjacent end beam or rafter B of the car-roof frame, but obviously each intermediate roofing-section,—that is, each roofing-section bridging the space between two adjacent carlines, has two upwardly projecting side portions 24 arranged over and extending along the adjacent carlines 85 respectively. An important feature of our invention is not only the opposite arrangement of adjacent flanged side portions 24 of adjacent roofing-sections L, but such a relative arrangement of said side portions that 90 they abut laterally against each other, and the provision of a desirable cap M for the said side portions of the said roofing-section, which cap covers and extends longitudinally of the flanges 25 of the said side portions 95 of the said roofing-sections and snugly engages the outer sides of the downwardly bent portions 26 of the said flanges. Preferably the portions 26 of the said flanges 100 of the said roofing-sections are so tightly engaged by the cap that the application of the cap to the said portions of the said flanges places the said portions of the said flanges under tension, so as to insure the reduction to a minimum of leakage of air 105 or other fluid at the joints formed between 110 said cap and said roofing-sections. 115

We would here remark that the adjacent side portions 24 of adjacent roofing-sections L and the curve or slope 23 of the said 120 roofing-sections over the carline overlapped in common by the said roofing-sections permit a limited expansion and contraction of the said roofing-sections without interfering with the maintenance of a snug engagement 125 130

between the adjacent roofing-cap M and the downwardly bent portions 26 of the flanges 25 of the said portions of the said roofing-sections.

5 Each cap M is provided externally and over the adjacent carline E with two laterally and outwardly projecting flanges 30 arranged at opposite sides respectively and extending longitudinally of the cap and resting on the said bodies of the roofing-sections L whose adjacent side portions 24 are covered by the said cap over the flanges of the said carline and over the side plates A, and the said cap is shown extending

10 from the outer side of each side plate A to the outer side of the other side plate, and at the outer side of each side plate (see Figs. 7, 10 and 11) has a downwardly projecting end-portion m arranged at the outer side of the adjacent downwardly projecting end-portions of the said roofing-sections and consequently at the outer side of the adjacent downwardly projecting end-portion of the said carline.

15 Each downwardly projecting end-portion m of each cap M is attached to the adjacent side plate preferably by means comprising a horizontally arranged bolt 32 and a nut 33. The said bolt 32 has its head arranged at the outer side of the said portion of the cap and has its shank extending horizontally through the said portion of the cap and through the adjacent downwardly projecting portion of the adjacent carline and through the adjacent side plate. The said nut 33 is screwed onto the said shank at the inner side of the said side plate, and a washer 34 is interposed between the said nut and the side plate.

20 By the construction hereinbefore described it will be observed that each end-portion m of each roofing-cap M forms an air-conducting passageway 28 which (see Figs. 7, 10 and 11) is arranged interiorly of and extends longitudinally of the said roofing-cap and communicates with the external atmosphere at the lower or outer extremity of the said end-portions of the said roofing-cap. The end-portions l of the roofing-sections L arranged adjacent each roofing-cap M are separated, as at 29, longitudinally of the adjacent side plate A, as shown in Figs. 10 and 11, so that the said passageway 28 in the said roofing-cap is in communication 25 with the interior of the adjacent trough-shaped carline, and consequently the roofing-caps and the carlines are kept ventilated. The space next under the flanges 25 of adjacent side portions 24 of adjacent roofing-sections is obviously also in communication with the passageways 28 formed interiorly of the end-portions m of the adjacent roofing-cap, and air also leaks between each flange 15 of the said carline and the adjacent 30 roofing-section L and at the seats 20 and 22

of the said carline for the ridge-pole and purlins, to the under sides of the body-portions of the roofing-sections L overlapping the said carline, and consequently the said sides of the bodies of the said roofing-sections and the interior of the car provided with our improved car-roof are adequately ventilated. The hereinbefore described ventilation of the component parts of the car-roof and the interior of a car provided with 70 the said roof successfully prevents sweating of the said roofing-parts and car-interior, and consequently the car is kept in a dry condition.

Any suitable number or all of the carlines E are each provided centrally between the ends of the respective carline with a rivet J which (see Figs. 3 and 4) is arranged horizontally and transversely of the said carline. The said rivet extends between the sides of 80 the said carline and is parallel with the ridge-pole F. The said rivet is embraced centrally between its ends by the eye 35 of an eye-bolt which has its shank 36 projecting vertically upwardly a suitable distance 85 above the said carline. It will be observed therefore that the said eye-bolt is arranged centrally between the sides and centrally between the ends of the said carline and connected to the carline. The said eye-bolt is 90 provided intermediate its upper extremity and the carline with a diametrical enlargement 37 which is spaced from the said carline and from the said extremity of the said bolt. The side portions 24 of the roofing-sections L overlapping the said carline extend transversely of the said eye-bolt between the ridge-pole and diametrical enlargement 37 of the eye-bolt and are respectively offset laterally and outwardly, as at 95 27, (see Figs. 3 and 8) to embrace the shank of the said bolt below the said diametrical enlargement of the bolt. It will be observed therefore that the roofing-sections overlapping the said carline have their adjacent 100 side portions 24 embracing opposite sides respectively of the said eye-bolt. The upper end face of the enlargement 37 of said eye-bolt forms an upwardly facing shoulder which is overlapped by an upwardly offset 105 portion 38 of the roofing-cap M which covers the flanges of said side portions 24 of said roofing-sections, and said upwardly offset portion of said cap extends around said eye-bolt and rests on said shoulder. Said 110 cap M is provided centrally between its ends with a cap K which forms the body of a saddle which is instrumental in supporting three running-boards G and has its top formed by a substantially horizontally arranged plate P. Said cap or saddle-body K is provided with two laterally and outwardly projecting flanges 40 extending longitudinally of and overlapping the flanges of the adjacent roofing-cap M. Said cap or saddle- 115 120 125 130

body K (see Fig. 4) has three seat-forming members 42 spaced longitudinally of the adjacent carline and arranged substantially in the same plane horizontally, and the central seat-forming member extends over and rests on the upwardly offset portion 38 of the adjacent roofing-cap M and extends around the adjacent eye-bolt above the shoulder formed by the enlargement 37 of 5 said eye-bolt. The aforesaid plate P is mounted on the seat-forming members 42 of the saddle comprising said plate, and a nut 39 is screwed at the upper side of said plate onto the shank of the adjacent eye-bolt, 10 which shank extends upwardly through the central seat-forming member 42 of said saddle and through said plate. Upon tightening said nut, said plate and the body of said saddle and the upwardly offset portion 38 of 15 the adjacent roofing-cap M are clamped by said nut against the upwardly facing shoulder formed by the upper end of the enlargement 37 of the eye-bolt engaged by said nut, and obviously by this construction is effected 20 the clamping to said shoulder of said roofing-cap and the running-board-saddle with which said roofing-cap is provided, without any interference with expansion and contraction of the roofing-sections extending 25 30 under said roofing-cap. In other words, the central portion of each roofing-cap M is provided with a running-board-saddle comprising three seat-forming members 42 which are spaced longitudinally of said roofing-cap 35 and arranged substantially in the same plane horizontally and carry a plate P over and across which the running-boards G extend. Said running-boards (see Figs. 1, 2, 3, 4, and 6) are shown arranged in the same 40 plane horizontally and extend longitudinally of and from end to end of the car-roof. The running-boards are secured at the ends of the car-roof (see Figs. 1, 2, and 6) to and supported from suitably applied brackets I. 45 The running-boards are shown secured to the central seat-forming members 42 of the running-board-saddles by suitably applied bolts R and nuts r, and the central running-board is recessed at its under side, as at g, to 50 accommodate the location of the eye-bolts and engaging nuts.

By the construction hereinbefore described it will be observed that not only is a joint formed between adjacent side portions or members 24 of adjacent roofing-sections L, but a joint is also formed between the outer portion 26 of each flange 25 of each of said roofing-sections and the adjacent side of the cap M covering said side 55 members, so that said side members and said cap are relatively contoured to form joints at the sides of the cap between the cap and said side members; that the last-mentioned joints, being arranged at the sides of 60 said cap, are located between the joint formed 65

between said side members and the roofing-sections and the external flanges 30 of said cap and consequently spaced from the last-mentioned joint; that a space is formed at each side of said cap below the joint formed 70 between said side of the cap and the adjacent side member of the adjacent roofing-section and that said space is arranged within and extends longitudinally of the cap and also extends from said side of the cap 75 to the lower portion of said side member of said roofing-section; that flooding of the carline arranged under the joint formed between adjacent side members of adjacent roofing sections is avoided because any water forced or driven at the under sides of the flanges 30 of the cap covering said side members into the spaces formed under the flanges 25 of said side members must be driven upwardly at and past the joints 80 formed between said cap and the flanges of said side members before it can reach the joint formed between said side members, and that any water that may reach the last-mentioned joint and perchance leak at said 85 joint into the trough of said carline is conducted off by said trough.

What we claim is:—

1. In car-roof construction, the combination, with the two laterally spaced side 95 plates, and a carline bridging the space between and connected to the side plates, of two roofing-sections extending from over said carline laterally of the carline in opposite directions and also extending longitudinally of the carline and over and beyond the outer sides of the side plates and having downwardly projecting end-portions at said sides of the side plates, each roofing-section 100 having an upwardly projecting side portion 105 arranged over and longitudinally of the carline and terminating in a flange which projects over the body of said roofing-section and extends longitudinally of said side portion of said roofing-section, and a cap covering and extending longitudinally of the flanges of adjacent upwardly projecting side 110 portions of the roofing-sections, which cap has downwardly projecting end-portions arranged at the outer sides of the downwardly 115 projecting end-portions of said roofing-sections and having interior air-conducting passageways which communicate with the external atmosphere at the outer sides of the side plates and are in communication 120 with the spaces formed next under the aforesaid flanges.

2. In car-roof construction, the two laterally spaced side plates; car-siding overlapping the outer sides of the side plates; a carline extending between and connected to the side plates; two metal roofing-sections extending over said carline and laterally of the carline in opposite directions and also 125 extending longitudinally of the carline and 130

- over the side plates and having downwardly projecting end-portions at the outer side of the aforesaid car-siding, each roofing-section having an upwardly projecting side portion arranged over and longitudinally of the carline and terminating in a flange which projects laterally of said side portion and over the body of said roofing-section and extends longitudinally of said side portion of said roofing-section, and a metal cap covering and extending longitudinally of the flanges of adjacent upwardly projecting side portions of the roofing-sections, said cap at the outer side of each side plate having a downwardly projecting end-portion arranged at the outer sides of the adjacent downwardly projecting end-portions of said roofing-sections, there being an air-conducting passageway formed between the inner side of each downwardly projecting end-portion of said cap and the adjacent downwardly projecting end-portions of said roofing-sections, said passageway communicating with the external atmosphere at the outer side of the adjacent car-siding and being in communication with the spaces formed next under the aforesaid flanges.
3. In car-roof construction, the combination, with the two laterally spaced side plates, and a carline comprising a trough extending at the top of the side plates from the outer side of one side plate to the outer side of the other side plate, of two roofing-sections extending from over said carline laterally of the carline in opposite directions and also extending longitudinally of the carline and over and beyond the outer sides of the side plates and having downwardly projecting end-portions at said sides of the side plates, each roofing-section having an upwardly projecting side portion arranged over and longitudinally of said carline, and a cap covering and extending longitudinally of adjacent upwardly projecting side portions of the roofing-sections, which cap has downwardly projecting end-portions arranged at the outer sides of the downwardly projecting end-portions of said roofing-sections and having interior air-conducting passageways which communicate with the external atmosphere at the outer sides of the side plates and are in communication between adjacent end-portions of the roofing-sections with the aforesaid trough.
4. In car-roof construction, the two laterally spaced side plates; car-siding overlapping the outer sides of the side plates; a carline comprising a trough extending from the outer side of the car-siding overlapping one side plate to the outer side of the car-siding overlapping the other side plate; two metal roofing-sections extending over said carline and laterally of the carline in opposite directions and also extending longitudinally of the carline and over the side plates and having downwardly projecting end-portions at the outer side of the aforesaid car-siding, each roofing-section having an upwardly projecting side portion arranged over and longitudinally of said carline, and a metal cap covering and extending longitudinally of adjacent upwardly projecting side portions of the roofing-sections, said cap at the outer side of each side plate having a downwardly projecting end-portion arranged at the outer sides of the adjacent downwardly projecting end-portions of said roofing-sections, there being an air-conducting passageway formed between the inner side of each downwardly projecting end-portion of said cap and the adjacent downwardly projecting end-portions of said roofing-sections, said passageway communicating with the external atmosphere at the outer side of the adjacent car-siding and being in communication between adjacent end-portions of the roofing-sections with the aforesaid trough.
5. In car-roof construction, a suitably supported carline comprising a trough; two metal roofing-sections extending over and longitudinally of said trough and laterally of the trough in opposite directions and having upwardly projecting side members extending above and longitudinally of said trough and making contact with each other over said trough, and a metal cap covering said side members and extending longitudinally of the carline, said side members and said cap being relatively contoured to form joints at the sides of said cap between the cap and said side members.
6. In car-roof construction, a suitably supported carline comprising a trough; two metal roofing-sections extending over and longitudinally of said trough and laterally of the trough in opposite directions and having upwardly projecting side members extending above and longitudinally of said trough and making contact with each other over the trough, and a metal cap covering said side members and extending longitudinally of the carline, said side members and said cap being relatively contoured to form joints at the sides of said cap between the cap and said side members, there being a space formed at each side of said cap adjacent the joint formed between said side of the cap and the adjacent side member of the adjacent roofing-section and said space being arranged within and extending longitudinally of the cap.
7. In car-roof construction, a suitably supported carline comprising a trough; two metal roofing-sections extending over and longitudinally of said trough and laterally of the trough in opposite directions and having upwardly projecting side members extending above and longitudinally of said

- trough and making contact with each other over the trough, and a metal cap covering said side members and extending longitudinally of the carline, said side members and 5 said cap being relatively contoured to form joints at the sides of said cap between the cap and said side members, there being a space formed at each side of said cap below the joint formed between said side of the 10 cap and the adjacent side member of the adjacent roofing-section and said space extending longitudinally of the cap and from said side of the cap to the lower portion of said side member of said roofing-section.
- 15 8. In car-roof construction, the combination, with the two laterally spaced side plates; a metal carline extending between and connected to the side plates; an upright bolt arranged between the sides and centrally between the ends of the carline, which bolt is connected to the carline and projects above the carline; two metal roofing-sections extending from over the carline laterally of the carline in opposite directions respectively and also extending longitudinally of the carline, each roofing-section having an upwardly projecting side portion arranged over and longitudinally of the carline, and a metal cap covering 20 and extending longitudinally of adjacent upwardly projecting side portions of the aforesaid roofing-sections, of another cap arranged centrally between the ends of the carline and extending over the first-mentioned cap and having three seat-forming portions spaced longitudinally of the carline and arranged substantially in the same plane horizontally, the central seat-forming portion extending around the bolt; a substantially horizontally arranged plate mounted on 25 the said seat-forming portions of the second-mentioned cap, and a nut screwed onto the bolt at the upper side of the said plate.
- 20 9. In car-roof construction, the combination, with the two laterally spaced side plates; a metal carline extending between and connected to the side plates; an upright bolt arranged between the sides and centrally between the ends of the carline, which bolt is connected to the carline and projects above the carline; two metal roofing-sections extending from over the carline laterally of the carline in opposite directions respectively and also extending longitudinally of the carline, each roofing-section having an upwardly projecting side portion arranged over and longitudinally of the carline, and a metal cap covering 25 and extending longitudinally of adjacent upwardly projecting side portions of the aforesaid roofing-sections, of another cap arranged centrally between the ends of the carline and extending over the first-mentioned cap and having three seat-forming portions spaced longitudinally of the carline and arranged substantially in the same plane horizontally, the central seat-forming portion extending around the bolt; a substantially horizontally arranged plate mounted on the said seat-forming portions of the second-mentioned cap, and a nut screwed onto the bolt at the upper side of the said plate.
- 30 10. In car-roof construction, the combination, with the two laterally spaced side plates; a metal carline extending between and connected to the side plates; an upright bolt arranged between the sides and centrally between the ends of the carline, which bolt is connected to and projects above the carline, of two metal roofing-sections extending from over the carline laterally of the carline in opposite directions respectively and also extending longitudinally of the carline, each of the said roofing-sections having an upwardly projecting side portion arranged over and longitudinally of the carline, said side portion of each roofing-section abutting laterally against the adjacent upwardly projecting side portion of the other roofing-section and having a laterally offset portion extending circumferentially of the bolt; a metal cap covering and extending longitudinally of the adjacent upwardly projecting side portions of the roofing-sections and holding the latter together; another cap arranged centrally between the ends of the carline and extending over and snugly engaging the sides of the said first-mentioned cap, said second-mentioned cap 35 extending around the bolt; a substantially horizontally arranged plate seated on the second-mentioned cap, and a nut screwed onto the bolt at the upper side of the plate.
- 35 11. In car-roof-construction, the combination, with the car-roof-frame, and two roofing-sections arranged on and extending transversely of said frame, of a metal cap arranged over and covering adjacent portions of said roofing-sections, and an upright member attached to the car-roof-frame and having a shoulder arranged under the top of said cap, and means clamping said cap to said shoulder, said cap resting on said shoulder independently of the operation of 40 said clamping means.
- 40 12. In car-roof-construction, the combination, with a suitably supported carline comprising a trough, and two metal roofing-sections extending over and longitudinally of said trough and laterally of the trough in opposite directions, of a metal cap covering adjacent portions of said roofing-sections and extending longitudinally of the carline, and an upright bolt arranged cen- 45

trally between the ends of and attached to the carline, said bolt being provided at the under side of the top of said cap with a shoulder and said cap resting at the under 5 side of its top portion on said shoulder.

13. In car-roof-construction, the combination, with the car-roof-frame, and two metal roofing-sections arranged over and extending transversely of said frame and having 10 upwardly projecting side members extending transversely of the car-roof-frame and into contact with each other, of a cap covering and extending longitudinally of said side members of said roofing-sections, and 15 an upright bolt attached centrally between the ends of said cap to the car-roof-frame and arranged between and embraced by said side members of the roofing-sections and having a shoulder arranged above said side 20 members, said cap resting on said shoulder.

14. In car-roof-construction, the combination, with a suitably supported carline comprising a trough, and two metal roofing-sections extending over and longitudinally of 25 said trough and laterally of the trough in opposite directions, of a metal cap covering adjacent portions of said roofing-sections and extending longitudinally of the carline, and an upright bolt arranged centrally between 30 the ends of and attached to the carline, said bolt being provided at the under side of the top of the cap with a shoulder, and said cap resting on said shoulder and embracing the cap at said shoulder.

35 15. In car-roof construction, the combination, with the two laterally spaced side plates; a carline extending between and connected to the side plates; an upright bolt arranged between the sides and centrally between the ends of the carline, which bolt is connected to and projects above the carline, said bolt being provided intermediate its upper extremity and the carline with a diametrical enlargement, and two metal roofing-sections extending from over the carline laterally of the carline in opposite directions 40 respectively and also extending longitudinally of the carline, each roofing-section having an upwardly projecting side portion 45 arranged over and longitudinally of the carline, of a metal cap covering and extending longitudinally of the adjacent upwardly projecting side portions of the roofing-sections and having an upwardly off-set portion 50 which extends around and over the aforesaid diametrical enlargement of the bolt; another cap arranged centrally between the ends of the carline and extending over the first-mentioned cap and 55 having an upwardly offset portion which extends around and over the aforesaid diametrical enlargement of the bolt; a substantially horizontally arranged plate mounted on the said seat-forming portions of the second-mentioned cap, and a nut screwed onto the bolt at the upper side of the plate.

ing three scattering portions which are 60 spaced longitudinally of the carline and arranged substantially in the same plane horizontally, the central seat-forming portion extending over the upwardly offset portion of the first-mentioned cap and around the 65 bolt; a substantially horizontally arranged plate mounted on the said seat-forming portions of the second-mentioned cap, and a nut screwed onto the bolt at the upper side of the plate. 70

16. In car-roof construction, the combination, with the two laterally spaced side plates, and a carline extending between and connected to the side plates, of an upright bolt arranged between the sides and centrally between the ends of the carline, which bolt is connected to the carline and projects a suitable distance above the carline, said bolt being provided intermediate its upper extremity and the carline with a diametrical enlargement; two metal roofing-sections 80 extending from over the carline laterally of the carline in opposite directions respectively and also extending longitudinally of the carline, each of the said roofing-sections 85 at a point between the sides of the carline having an upwardly projecting side portion which extends longitudinally of the carline and terminates in a flange projecting laterally and extending longitudinally of the said 90 side portion; a metal cap covering and extending longitudinally of the flanges of the adjacent upwardly projecting side portions of the said roofing-sections and having an upwardly offset portion which extends around 95 and over the aforesaid diametrical enlargement of the bolt; another cap arranged centrally between the ends of the carline and extending over the first-mentioned cap and 100 having three seat-forming portions which are spaced longitudinally of the carline and arranged substantially in the same plane horizontally, the central seat-forming portion extending over the upwardly offset portion of the first-mentioned cap and around 105 the bolt; a substantially horizontally arranged plate mounted on the said seat-forming portions of the second-mentioned cap, and a nut screwed onto the bolt at the upper side of the plate. 110
